UNITED STATES PATENT OFFICE.

WALTER J. BARRON, OF NEW YORK, N. Y., ASSIGNOR TO DENSMORE TYPEWRITER COMPANY,
OF SYRACUSE, NEW YORK, A CORPORATION OF NEW YORK.

TYPE-WRITING MACHINE.

No. 917,745.

Specification of Letters Patent. Patented April 13, 1909.

Application filed February 6, 1902. Serial No. 92,843.

To all whom it may concern:

Be it known that I, WALTER J. BARRON, a citizen of the United States, and resident of the borough of Brooklyn, city of New York, 5 in the county of Kings and State of New York, have invented certain new and useful Improvements in Type-Writing Machines, of which the following is a specification.

My invention relates to escapement mechanism for typewriting machines and to mechanism for moving the carriage back to the right a letter space distance at a time.

One object of the invention is to provide a simple, strong, rapid and efficient escapement mechanism and one wherein the same escapement may be used to feed the carriage either on the down stroke, the up stroke, or on both the down and up stroke of a key lever, whereby the escapement may be readily set to provide an "ordinary", "reverse", or double letter space feed of the carriage.

Another object of the invention is to produce a simple and efficient device for stepping the carriage back to the right a letter space distance at a time, in order to insert one or more characters which may have been omitted in the operation of the machine or to make such other corrections or insertions as may be required. This last mentioned 20 device is likewise valuable in the production of tabulating work, in which it may be employed as a means for manually feeding the carriage back from a given point in a direction opposite to that of the normal or automatic feed of the carriage.

To the above ends and others which will appear in the following specification, my invention consists in the novel construction and arrangement and combinations of parts 40 to be hereinafter described and particularly pointed out in the concluding claims.

In the accompanying drawings, wherein like reference characters designate like parts in the various views, Figure 1 is a vertical sectional view of a sufficient number of parts of one form of typewriting machine to illustrate my invention, the section being taken from front to rear of the machine. Fig. 2 is an enlarged detail rear elevation of a portion 50 of the structure illustrating the carriage feed mechanism. Fig. 3 is a side view of the same. Fig. 4 is a view which corresponds to that shown in Fig. 3 except that certain of the parts are omitted and those shown are 55 illustrated in different positions from those

represented in Fig. 3. Fig. 5 is a view corresponding to Fig. 4 except that the parts are shown in different positions. Fig. 6 is a detail perspective view of the dogs and coöperating switch the view being taken from the 60 opposite side from that shown in Figs. 3, 4 and 5. Fig. 7 is a detail front view with parts broken away of the so-called gig-back device. Fig. 8 is a like view of the same; the view illustrating the positions the parts as- 65 sume in the operation of the device. Fig. 9 is a rear perspective view of the gig-back device; the parts being shown in the operative position.

In the drawings, 1 designates the framing 70 of the machine, in which the key levers 2 are pivoted at 3 and each key lever is provided with the usual finger key 4, and has extending therefrom a hook or abutment 5 which coöperates with a universal bar 6 that is pro- 75 vided with rearwardly extending arms 7, the rear ends of which arms are pivoted at 8 to the framing of the machine. It will be understood that this universal bar extends beneath all of the hooks or abutments 5 on 80 the various key levers. Each key lever 2 is also connected to a suitable link 9, which in turn is pivoted at 10 to an actuating lever 11 that is pivoted at 12 to a hanger 13 and is operatively connected at 14 to a type bar or 85 carrier 15 that is also pivoted at 16 to the hanger 13.

The universal bar 6 has pivoted thereto at 17 a link 18, the upper end of which is pivoted at 19 to an arm 20 of the feed dog 90 carrier 21. This feed dog carrier is pivoted at 22 to a bracket or casting which is secured to the top-plate of the machine and the feed-dog carrier carries headed pins or screws 23 which project through elongated openings or 95 slots 24 in the movable feed dogs 25 and 26 and additional screws 27 may project through elongated openings 28 in the feed dogs to guide them in their vertical movements. The pins or screws 23 and 27 and the co- 100 operating openings 24 and 28 are in the nature of pin and slot connections which permit the feed dogs to receive a vertical movement on the feed dog carrier 21, and each of these feed dogs coöperate with a contractile 105 spring 29 which tends to move it upwardly. The upper end of each feed dog 25 and 26 is bent at substantially right angles to the body thereof as indicated at 30 and 31 in Fig. 6 of the drawings, for coöperation with a feed 110

wheel 32 that is operatively connected to one end of a shaft 33 which is mounted in a bearing 34 secured to the top plate 35 of the machine. The forward end of this shaft 33 has secured thereto a feed pinion 36 which meshes with a feed rack 37 carried by the carriage 38, which carriage may have mounted to rotate therein the usual or any preferred platen 39.

Upon reference to Fig. 2 of the drawings it will be seen that the springs 29 hereinbefore referred to are each connected at one end to a pin 40 that is carried upon the feed dog carrier, whereas the opposite end of each of these springs is connected to a pin 41 which is secured to its coöperating feed dog and projects through the elongated slot in the feed dog carrier as shown in dotted lines at 42. The bent end of the feed dog 25 is limited in its downward movement by an abutment 43 formed by the upper end of the feed dog carrier, and this abutment for limiting the downward movement of the feed dog 25 on a lower level than the corresponding abutment 44 of the feed dog 26, as shown in Figs. 3, 4 and 5 of the drawings. From this it will be seen that under certain conditions which are represented in Fig. 3, the operative face of the feed dog 26 is on a slightly higher level than the corresponding operative face of the feed dog 25, when the dog 26 is in engagement with a tooth of the feed wheel for purposes which will hereinafter appear.

The feed dogs 25 and 26 are provided with locking notches or depressions 45 and 46 respectively and coöperating with these locking notches are locking fingers 47, 48, which are carried by a so-called lock or switch 49 that is pivoted to the feed dog carrier at 50 so that the pivot thereof is coincident with the pivots 22 of the feed dog carrier. This switch has a laterally extending arm 51 which terminates in a finger piece 52 by which it may be moved to any one of several positions. The feed dog carrier 21 has a spring arm or lock 54 secured thereto at 53, the pointed end 55 of said arm being adapted to seat itself in any one of the three recesses or depressions 56 in the body of the switch in order to maintain it in any one of the three positions to which it may be moved by its finger piece 52. This switch 49 carries a depending arm 57 which is provided with a stop or abutment 58 which, when the parts are in the position represented in Fig. 5 of the drawings bears at its lower end upon one of the screws 23 so that the screw forms a rigid support therefor while the stop is interposed in the path of a stop pin or abutment 59 carried by the feed dog 25. Adjacent to the stop 58 on the switch is a recessed portion 60 which is brought into the path of the pin 59 on the feed dog when the switch has been moved to the position indicated in Fig. 3 of the drawings. The dotted lines *a* in Fig. 5 of

the drawings indicate the limit of downward movement of the feed dog 25 when the stop is interposed in the path of its coöperating stop 59 on the feed dog. In this position of the parts it will be observed that the upper or operative face of the feed dog 25, which is indicated by the uppermost dotted line *a* will be maintained on a higher level than the upper or operative face of the feed dog 26 for purposes which will hereinafter appear. 75

When the lock or switch is set in the position shown in Figs. 1 and 3 of the drawings, the locking finger 47 thereof will be forced into the notch 45 of the feed dog 25 so as to maintain it against vertical movement. At 80 this time the feed dog 26 is free to move in a vertical direction on the feed dog carrier. This arrangement of the parts is such that the "natural" or "ordinary" feed of the carriage is produced; that is to say, the carriage 85 will be fed on the upstroke of the key. Thus a depression of one of the keys 4 will cause the universal bar 6 to be depressed, thereby drawing down the link 18 and transmitting a vibratory movement to the feed dog carrier 90 on its pivotal center 22, so that the feed dogs are rocked toward the front of the machine. These movements of the parts are effective to release the feed dog 26 from the feed wheel 32 and the dog 25, which at this time 95 is a fixed dog, comes into contact with the same tooth of the wheel which was engaged by the movable feed dog 26 to prevent a rotation thereof. The feed dog 26 having been released in the manner specified will be 100 moved upwardly by its spring 29 to a position where it is adapted to coöperate with the next succeeding tooth of the feed wheel and when the operator releases the key 4 the dog carrier will move toward the rear of the 105 machine, thus disengaging the fixed dog 25 from the tooth of the wheel with which it was in engagement and at the same time the loose dog will be moved into the path of the next succeeding tooth. The carriage will 110 then be fed in the direction of its feed one letter space distance under the tension of the carriage spring which is effective to depress the dog 26 against the tension of its spring, and the parts will again be arrested in the 115 position indicated in Fig. 3. From this it will be seen that the feed movement of the carriage has taken place on the upstroke or release of the finger key. As before explained, when the parts are in this position 120 the upper or operative face of the dog 26 will be maintained on a higher level than the corresponding face of the other feed dog. This is in order to prevent any wear on the operative face of the dog 26 from interfering with 125 the proper operation of the escapement which ordinarily might result in a side of the other feed dog coming into contact with the side of the tooth of the feed wheel during the feed movement. It will be understood that in 130

the present structure it will require considerable wear, and more than the dog is liable to receive, to bring the operative face thereof to a lower level than the corresponding face of the other dog thus avoiding any interference in the operation of the escapement through the wear on the feed dog 26.

In order to set the escapement device for "reverse" feed it is merely necessary to move the switch from the position represented in Figs. 1 and 3 of the drawings to that shown in Fig. 5, when the locking finger 47 will be withdrawn from engagement, and the finger 48 will be engaged in the coöperating notch 46 in the feed dog 26. In these positions of the parts the dog 26 becomes the locking or fixed dog, whereas the dog 25 is the feed or movable dog. In operation a depression of a key 4 will cause the dog carrier to move the dogs in the direction of the arrow in Fig. 5, or toward the front of the machine, when the feed wheel will be released from the dog 26 and the next succeeding tooth will, by the same movement, be brought into engagement with the loose dog 25 and the carriage will be fed under the pressure of its spring, thus forcing the loose dog against the tension of its spring, so that the carriage is fed on the depression of the finger key. When the operator releases the pressure from the key the movable dog 25 will be moved away from the tooth of the feed wheel which maintains it under pressure and the fixed dog 26 will, at the same time, be brought into engagement therewith, so that no movement of the feed wheel and the carriage is permitted on this upward movement or release of the key.

As before explained, when the switch is in the position represented in Fig. 5 the operative face of the feed dog 25 which is indicated by the uppermost dotted line *a* will be maintained on a higher level than the feed dog 26, by reason of the fact that the abutment 58 has been interposed, by the movement of the switch, into the path of the coöperating abutment or pin 59 on this feed dog, to limit the downward movement thereof, so that any wear which takes place upon this dog 25 will be ineffective to prevent a proper feed of the parts by the side of the feed dog coming into contact with the side of a tooth of the feed wheel which would result in arresting the movement of the dog carrier and preventing a proper operation of the escapement.

From the foregoing description, it will be understood that whether the escapement be set for the "natural" or "ordinary" or for "reverse" feed the operative face of the loose dog is always maintained on a higher level or in advance of the corresponding face of the fixed dog so that any wear which takes place upon the dogs cannot act injuriously in the operation of the escapement.

65 When the operator desires to provide a

double letter space feed for making headings and the like, it is merely necessary to move the switch to the intermediate position illustrated in Fig. 4, when both of the locking fingers 47 and 48 are maintained out of locking engagement with their coöperating locking recesses 45 and 46 respectively, and both feed dogs are adapted to move vertically. In Fig. 4 both of these dogs are illustrated in the elevated position, though it should be understood that the pressure of the carriage spring upon the feed wheel will normally maintain the feed dog 26 depressed against the tension of its spring. A depression of a finger key 4 will move the dogs toward the front of the machine, thereby releasing the feed dog 26 from the engaged tooth of the feed wheel and simultaneously interposing the feed dog 25 in the path of the next succeeding tooth of the wheel. When the feed dog 25 has been thus interposed in the path of this next succeeding tooth of the feed wheel the tension of the carriage spring will overcome the spring 29 of the dog 25, forcing the dog downwardly to the limit of its movement. The same movement of the parts having released the feed dog 26 from the wheel, the tension of the spring of the dog will force it upwardly and to a position to co-operate with the next succeeding tooth of the feed wheel when the dog carrier is again moved toward the rear of the machine. A release of the finger key by the operator will be effective to bring about this rearward movement of the dogs thereby engaging the feed dog 26 with the coöperating tooth of the feed wheel and simultaneously releasing the feed dog 25. From this it will be seen that a feed of the carriage is produced both on the down stroke and up stroke of each key, and that a double letter space feed is provided at each operation of a key lever.

In the various movements of the switch to the positions hereinbefore described, the spring arm 54 will be forced against the tension of its spring by the inclined sides of its pointed end coming into contact with the walls of the coöperating recesses 56. When, however, the switch is properly positioned in any one of the three positions described, the pointed end of the lock or spring arm 54 will be properly positioned in the center of its coöperating recess, so as to lock and maintain the switch in the set position. 110 115

Suitable means may be provided to limit the movement of the feed dog carrier in opposite directions in order to regulate the timing of the escapement; thus I have shown in the present instance a lug 61 which is secured to the top plate of the machine at 62 and has a screw-threaded opening with which an adjustable screw 63 co-operates. The rear end of this screw may be provided with a suitable buffer 64 that is adapted to receive the impact of the feed dog carrier and 130

thereby limit the movement thereof toward the front of the machine. A lock nut 65 may likewise be employed to secure the screw in the adjusted position. It will be understood that suitable means may also be provided to limit the movement of the feed dog carrier in an opposite direction, and thereby nicely regulate the feed action of the escapement.

While I have shown and described with considerable detail one form of escapement mechanism embodying my invention, it should be understood that from certain aspects of the invention it is immaterial what character of escapement mechanism is employed. For instance, while I have shown one feed element (the rack 37) carried by the carriage, whereas another feed element (the feed wheel 32) is carried by the framing of the machine and intermediate mechanism (the shaft and feed pinion) is interposed between the two feed elements to operatively connect them, it is obvious that the connection may be a direct one, and that the feeding instrumentalities may be varied to apply the principle of my invention to type-writing machines of different characters from that shown and described. It should also be understood that any one or more of the features of my new escapement mechanism may be employed without the others and without departing from the spirit of the invention as defined in the appended claims.

I will next describe the so-called gig-back device whereby the carriage may be stepped back toward the right, a letter space distance at a time. The front rail 70 of the carriage has a supporting bracket 71 secured thereto at 72 and this bracket carries a bearing 73 for a short rock shaft 74 which has a crank arm or finger piece 75 secured to the forward end thereof and extending toward the right hand side of the machine as illustrated in Figs. 7 and 8. The rear end of the rock shaft has a depending crank arm 76 secured thereto and to the lower end of which is pivoted at 77 a gig-back pawl 78 that is adapted to coöperate with a rack bar 79 that extends throughout the extent of travel of the carriage and the teeth 80 of which extend toward the right. This rack bar is preferably carried by the shift rail 81 so as to move therewith during the transverse shifting movement of the platen but to remain fixed with relation to the travel of the carriage though obviously the rack bar may be otherwise arranged. The pawl 78 is provided with a tail piece 82 which extends beyond the pivot of the pawl and this tail piece as well as the pawl itself is flattened on the upper side thereof for coöperation with the under-side of the front carriage rail which constitutes an abutment therefor. The parts are normally maintained in the positions shown in Fig. 7 by a spring 83 which is connected at one end 84 to the rail 70 and at

its opposite end 85 bears on the under side of the finger piece 75. The pressure thus exerted upon the parts maintains the pawl out of engagement with its rack by forcing the tail of the pawl against the bottom of the rail 70. When however, the finger piece 75 is depressed this pressure will be released and the spring 86 which is secured at 87 to the crank arm 76 becomes effective to move the pawl around its pivot and into engagement with the teeth 80 of the rack as shown in Fig. 8. A further depression of the finger piece to the dotted line position in Fig. 8 is effective to vibrate the arm 76 and thus cause the carriage to be moved one letter space distance to the right. A series of quick depressions of the finger piece 75 is effective to step the carriage back any desired number of letter space distances.

The gig-back arrangement is a valuable aid in the production of tabulating or billing work. Thus we will suppose that a bill to be written is as follows:

Coal	-----	\$748.44	90
Wood	-----	58.00	
			806.44

In this event it is merely necessary to write the word "coal" and to depress the carriage release key, thus permitting the carriage to move to the left until a predetermined point, say "65" on the carriage scale, is reached and which will correspond to the units column and then to mentally read off the amount and to depress the finger piece 75 for each character involved in the mental reading. This operation of the finger piece for the first amount mentioned above will manually feed the carriage in a direction reverse to that of its ordinary or automatic feed movement, seven letter space distances and the operator may then proceed to write the amount "\$748.44". The next amount may be written in the same manner, the carriage in each instance being arrested at the point determined on for the units column, which I have assumed to be 65 and each time the carriage will be fed back by the gig-back device the requisite number of letter space distances; the number of such distances depending on the number of characters employed in the sum to be written.

What I claim as new and desire to secure by Letters Patent is:—

1. In a typewriting machine, the combination of type carriers, means for actuating said type carriers, a carriage, a feed element on the carriage, a pair of coöperating independently movable feed dogs on the framing of the machine, and hand operated regulating means for locking one or freeing both of said feed dogs so that one or both dogs may be made stepping dogs and the carriage can be fed one or more letter space distances at

each operation of the type carrier actuating means, in accordance with the positioning of said hand operated regulating means.

2. In a typewriting machine, the combination of type carriers, means for actuating said type carriers, a carriage, a feed element on the carriage, a plurality of coöperating movable feed dogs which are movable in two directions, a hand operated lock coöperating with said feed dogs so that the carriage can be fed "ordinary" or "reverse" or can be fed more than one letter space distance at each operation of the type carrier actuating means in accordance with the positioning of said hand operated lock, and a movable stop which is moved into the path of and limits the movement of one dog when another is locked, whereby the operative face of one dog will be maintained above the corresponding face of the other dog.

3. In a typewriting machine, the combination of a dog carrier, a pair of feed dogs which are movable in two directions, a feed rack which coöperates with said dogs and a locking switch carried by said dog carrier for locking either of said dogs against movement in one direction or maintaining both of them free to move in both directions, whereby an "ordinary" "reverse" or a plurality of letter space distance feed may be provided.

4. In a typewriting machine, the combination of a dog carrier, a pair of feed dogs which are movable in two directions, a feed rack which coöperates with said dogs, a locking switch carried by said dog carrier for locking either of said dogs against movement in one direction or maintaining both of them free to move in both directions, whereby an "ordinary" "reverse" or a plurality of letter space distance feed may be provided and means for locking the switch against movement with relation to the dog carrier.

5. In a typewriting machine, the combination of a pair of longitudinally and laterally movable spring pressed feed dogs, means for maintaining either of said dogs locked against the tension of its spring or for maintaining both dogs free to be moved by their springs and means which coöperate with the feed dogs to feed the carriage, whereby an "ordinary" "reverse" or double letter space feed may be provided at will.

6. In a typewriting machine, the combination of a pair of longitudinally and laterally movable spring pressed feed dogs, a locking element carried by each of said dogs, a locking switch which has locking elements that are adapted to coöperate with the locking elements on the feed dogs, means for maintaining the locking switch in position where it will coöperate with either dog or be out of coöperation with both dogs, for maintaining either of said dogs locked against the tension of its spring or for maintaining both dogs free

to be moved by their springs and means which coöperate with the feed dogs to feed the carriage, whereby an "ordinary" "reverse" or double letter space feed may be provided at will.

7. In a typewriting machine, the combination of a vibratory dog carrier, a pair of spring pressed notched feed dogs carried thereby and movable thereon, a switch which is pivoted to said dog carrier and adapted to engage in the notch of each feed dog to lock it against movement on the dog carrier or to be maintained out of locking engagement with both dogs and a feed element coöperating with said feed dogs whereby an "ordinary" "reverse" or double letter space feed may be provided at will.

8. In a typewriting machine, the combination of a vibratory dog carrier, a pair of spring pressed notched feed dogs carried thereby and movable thereon, a switch which is pivoted to said dog carrier and adapted to engage in the notch of each feed dog to lock it against movement on the dog carrier or to be maintained out of locking engagement with both dogs, a feed element coöperating with said feed dogs whereby an "ordinary" "reverse" or double letter space feed may be provided at will and a stop which is carried by said switch and which is moved into the path and limits the movement of one dog when the other is locked.

9. In a typewriting machine, the combination of type carriers, a vibratory dog carrier, means for moving said dog carrier at each operation of the type carrier, a pair of spring pressed notched feed dogs carried by said dog carrier and movable thereon, a switch which is pivoted to said dog carrier and adapted to engage in the notch of each feed dog to lock it against movement on the dog carrier or to be maintained out of locking engagement with both dogs, means for securing the switch in any one of the various positions to which it may be moved and a feed element coöperating with said feed dogs whereby an "ordinary" "reverse" or double letter space feed may be provided at will.

10. In a typewriting machine, the combination of type carriers, key levers therefor, a power driven carriage, a feed wheel operatively connected to the carriage, a vertically mounted vibratory feed dog carrier, independently movable spring pressed feed dogs coöperating with the feed wheel and mounted to move vertically on said carrier, the coöperating feeding projection of each dog extending at substantially right angles to the body thereof, means for vibrating the dog carrier at each operation of a type carrier and means for locking either of said dogs against vertical movement or for permitting both dogs to move vertically, whereby the carriage may be fed either on the depression

- or on the upward movement or on both the depression and upward movement of a key lever.
11. In a typewriting machine, the combination of type carriers, key levers therefor, a power driven carriage, a feed wheel operatively connected to the carriage, a vertically mounted vibratory feed dog carrier, independently movable spring pressed feed dogs 10 coöperating with the feed wheel and mounted to move vertically on said carrier, the co-operating feeding projection of each dog extending at substantially right angles to the body thereof, means for vibrating the dog carrier at each operation of a type carrier, means carried by the dog carrier for locking either of said dogs against vertical movement when the other is unlocked or for permitting both dogs to move vertically, where- 15 by the carriage may be fed either on the depression or on the upward movement or on both the depression and upward movement of a key lever, and means for retaining the dog locking means in its set position.
12. In a typewriting machine, the combination of a carriage and an escapement therefor, said escapement comprising movable feed dogs, means for locking either of said dogs against movement, and means for con- 20 trolling the movement of the unlocked dog so that the operative face thereof will be in advance of the operative face of the locked dog, to prevent the wear on the dogs from interfering with their feeding operation.
13. In a typewriting machine, the combination of a carriage and an escapement therefor, said escapement comprising movable feed dogs, hand operated means for locking either of said dogs against feed movement 25 and means controlled in part by said locking means for controlling the movement of the unlocked dog so that the operative face thereof will at all times be in advance of the operative face of the locked dog, to prevent the wear on the dogs from interfering with their feeding operation.
14. In a typewriting machine, the combination of a carriage and an escapement therefor, said escapement comprising movable feed dogs, means for locking either of said 30 dogs against movement to provide an "ordinary" or "reverse" feed at will, means which are hand operated and movable in part for limiting the movement of the un- 35 locked dog in one direction so that an operative face thereof will at all times be in advance of the operative face of the locked dog, to prevent the wear on the dogs from interfering with their feeding operation.
15. In a typewriting machine, the combination of a carriage and an escapement therefor, said escapement comprising movable feed dogs, means for locking either of said dogs against movement, a relatively fixed 40 abutment which limits the movement of one 45 of said dogs in one direction and a relatively movable abutment which is adapted to coöperate with the same dog to limit its movement in the same direction but at a different point whereby the operative face 70 of the unlocked dog can be maintained in advance of the locked dog at all times.
16. In a typewriting machine, the combination of a carriage and an escapement therefor, said escapement comprising movable feed dogs, a hand operated switch for locking either of said dogs against movement and an abutment carried by said switch and adapted to coöperate with an unlocked dog 75 to limit its feed movement and to maintain 80 the operative face thereof in advance of the locked dog.
17. In a typewriting machine, the combination of a carriage and an escapement therefor, said escapement comprising movable feed dogs, means for locking either of said dogs against movement, a relatively fixed abutment which limits the movement of said dogs in one direction, and a relatively movable abutment which is controlled in its 85 movement by the locking means and which is adapted to coöperate with one of the dogs to limit its movement in the same direction that it is limited by the relatively fixed abut- 90 ment but at a different point, whereby the 95 operative face of the unlocked dog can be maintained in advance of the locked dog at all times.
18. In a typewriting machine, the combination of an escapement therefor, said escapement comprising a dog carrier and feed dogs which are movable on said carrier, a stop on the carrier for limiting the movement of one of the dogs in one direction on the carrier, a switch carried by the carrier 100 and adapted to lock either of said dogs against movement on the carrier, a fixed abutment on the carrier which coöperates with one of the dogs to limit its movement in one direction and a stop on the switch 105 which coöperates with the same dog to limit the movement thereof in the same direction whereby the operative face of the unlocked dog will always be in advance of the locked dog.
19. In a typewriting machine, the combination with an escapement which can work either "ordinary" or "reverse" feed and means for maintaining the feeding element of the escapement in advance of the 110 fixed or retaining element whether the escapement be working "ordinary" or "re- 115 verse" feed.
20. In a typewriting machine, the combination of type carriers, means for actuating said type carriers, a feed element, a pair of coöoperating independently movable feed dogs coöperating with said feed element, and a single hand-operated regulating means for locking either one or freeing both of said 120 125 130

feed dogs so that either or both feed dogs may be made stepping dogs and the carriage may be fed one or more letter space distances at each operation of a type carrier 5 actuating means in accordance with the positioning of said single hand-operated regulating means.

21. In a typewriting machine, the combination of type carriers, means for actuating the type carriers, a carriage, a feed element, a pair of coöperating feed dogs which are movable in two directions, and a single hand-operated lock coöperating with said feed dogs for locking either of said dogs in 10 one position or freeing both dogs so that the carriage can be fed "ordinary" or "reverse" or can be fed more than one letter space 15 distance at each operation of the type carrier actuating means in accordance with 20 the positioning of said single hand-operated lock.

22. In a typewriting machine, the combination of type carriers, means for actuating said type carriers, a carriage, a feed element, a pair of independently movable feed dogs which coöperate with said feed element and which are movable in two directions, a single hand-operated lock coöperating with 25 said feed dogs for locking either of said dogs in one position or freeing both dogs so that the carriage can be fed "ordinary" or "reverse" or can be fed more than one letter 30 space distance at each operation of the type carrier actuating means in accordance with 35 the positioning of said single hand-operated lock, and a movable stop which is moved

into the path of and limits the movement of one dog when another is locked, whereby the operative face of one dog will be maintained above the coöperating face of the other dog. 40

23. In a typewriting machine, the combination with a carriage of an escapement mechanism comprising means for obtaining an ordinary feed, means for obtaining a reverse feed and means for obtaining a double 45 feed of the carriage.

24. In a typewriting machine, the combination of a platen, a power driven carriage which carries said platen, escapement mechanism for the carriage, a pivoted gig-back 50 pawl independent of the escapement mechanism, a finger key for actuating said pawl, a bracket detachably connected to the carriage at the front thereof and carrying said gig-back pawl and its actuating finger 55 key so that the latter is readily accessible to the operator, and a rack which is fixed against travel with the carriage and extends in the direction of the travel of the carriage, the gig-back pawl being normally out of 60 engagement with said rack but coöoperative therewith at any point in the travel of the carriage to effect a step-by-step backward feed movement of the carriage.

Signed at the borough of Manhattan, city 65 of New York, in the county of New York, and State of New York, this fourth day of February A. D. 1902.

WALTER J. BARRON.
